UNITED STATES PATENT OFFICE.

FRANZ SCHULDES, OF NEW YORK, N. Y.

PLANING MACHINE.

Application filed August 20, 1924. Serial No. 733,101.

To all whom it may concern:

Be it known that I, FRANZ SCHULDES, a citizen of the United States, residing at New York, in the county of New York and State 5 of New York, have invented certain new and useful Improvements in Planing Machines, of which the following is a specification.

This invention relates to improvements in planing machines, particularly machines for automatically leveling comparatively wide surfaces of wood by cutting consecutive sweeps of a predetermined width thereon.

It is the principal object of the invention to provide such a planing machine with 15 means for positively advancing the cutting or planing tool or tools for a predetermined distance after each operation, and to perform its operation in a positive and efficient manner, while having a comparatively simple and inexpensive construction.

Another object of the invention is to provide a planing machine in which the work-piece is located on a carriage receiving a 25 step by step intermittent motion during the operation of the machine.

A further object of the invention is the provision of a machine of this character with means for causing the tool carrying arm to dwell for a short time at the end of its 30 stroke.

These and other objects of my invention will become more fully known as the description thereof proceeds, and will then be 35 specifically pointed out in the appended claims.

In the accompanying drawing forming a material part of this disclosure:

Figure 1 is a top plan view of a planing machine constructed in accordance with the 40 present invention.

Figure 2 is a front elevation thereof.

Figure 3 is a longitudinal vertical section on line 3—3 of Figure 1.

Figure 4 is a section on line 4—4 of Figure 3.

Figure 5 is a partial end elevation seen in the direction of the arrow 5, Figure 1.

Figure 6 is a front elevation of the parts shown in Figure 5.

Figure 7 is an enlarged detail view of the clutch mechanism in approximately the center of Figure 2.

Figure 8 is a fragmentary top plan view of the front end of the oscillating arm.

55 A stationary divided machine bed 10 carries the uprights 11 of the machine frame

connected by lower cross-bars 12, and an upper beam 13. The upper faces of the parts of the bed 10 are provided with guide grooves in which ridges or ribs 14 on the 60 underside of a carriage 15 are guided to carry the work-piece 16 held thereon in any suitable manner to be engaged by a planing tool 17 adapted to sweep in consecutive arcs over the surface of the work-piece. In order to effect a reciprocation of the carriage, the side edges thereof carry racks 18 engaged by the teeth of operating wheels, as will hereafter be more fully described.

The beam 13 carries, at its upper face 70 near one end thereof, a motor 19, the shaft 20 of which carries a belt pulley 21 over which a belt 22 is guided which is also guided over a pulley 23 on a vertical shaft 24 revolving in an upper bearing 25 resting 75 with its flange on beam 13. The lower end of shaft 24 revolves in a bearing 26 in the machine frame part 27. Intermediate its ends, shaft 24 revolves in a bearing 28 in part 29 of the machine frame, and between the bearings 25 and 28, the shaft carries an enlarged part 30 equipped with an exterior worm 31.

Upon shaft 24 near its lower end, and between bearings 26 and 28 is fulcrumed an 85 oscillative arm composed as shown, of an upper member 32 and lower member 33. In the forward end of the arms 32—33, is supported the spindle 34 of the cutting or planing tools 35, 36. The spindle 34 is rotated from shaft 24 at an increased speed 90 by means of a belt 37 guided over a pulley 38 on shaft 24 and a pulley 39 on spindle 34. The spindle 34 is held in its conical bearings by a plate 40 longitudinally extending on the front part of arm 32.

In brackets 42 secured to the lower face of beam 13, a shaft 43 is journalled which carries a worm wheel 44 in mesh with the worm 31 of the shaft 24 and near its opposite end shaft 43 carries a sprocket wheel 44a over which a chain 45 is guided which is trained over a sprocket wheel 46 on a shaft 47 for a purpose hereafter more fully to be described.

An arm 48 projecting from the sides of the beam 13 carries a transverse shaft 49, the ends of which are journalled in the upper ends of brackets 50, 51 in the machine frame. Near its ends the shaft 49 carries 110 bevel gears 52 and 53 in mesh with bevel gears 54 and 55 on top of vertical shafts

56 and 57 which carry gear wheels 58 and 59 in mesh with the teeth of racks 18 on carriage 15. Intermittent motion, if so desired, is transmitted to the carriage by 5 means of the sprocket wheel 60 and the chain 61 guided over a sprocket wheel 62 on shaft 47.

The arms 32 are oscillated by means of a pair of cables 63, 64 attached, at their inner 10 end, to an eye 65 secured to the outer end of arm 32. The opposite ends of these cables are run around guide rollers 66 and 67 and wound upon a pair of arbors 68 and 69 journalled in the machine frame, and 15 alternately rotated in the following manner:—

The rotation of the power shaft 47 is effected from the motor driven shaft 24 by the above described connections. The shaft 20 47 revolves with a spindle 70 and has the form of a sleeve to the end of which is slidably connected, by a key and slot a clutch member 71 cooperating with another clutch member 72.

25 This second clutch member is adapted to turn arbor 68 by gear transmission 73. The opposite end of the shaft 47 is arranged to rotate arbor 69, the construction being such, that when one clutch 71, 72 is 30 opened, the other clutch is closed, as illustrated in Figure 1 in which the right hand clutch is shown closed, and the left hand clutch is open. An operating arm 74 has adjustably attached thereto, as at 75, an 35 operating lever 76 carrying a weight 77, at its upper end, and the arm 74 carries fingers 78 which operatively engage the clutch members 71.

In order to cause arm to dwell for a short 40 time at the end of each stroke, the following mechanism is provided:—At some distance below arbors 68 and 69 levers 79 carrying weights 80 are pivoted in brackets 81 of the machine frame normally supporting 45 slotted links 82, to the upper end of which are pivotally connected links 83, the lower ends of which are weighted as at 84, and carry rollers 85 on shafts 86. The construction is such that when the lever 79 is lowered as indicated in Figure 5, the rope 64 50 will be relaxed, or in other words, the path of the rope will be shorter when the arm or lever 79 is raised, than when it is lowered. The shaft 86 carries a pointer 87 and 55 is vertically movable in a longitudinal slot 88 of a dial 89 bearing graduations on its outer face, as illustrated in Figure 5, allowing an adjustment of the width of the sweep to be cut by the tool in the work-piece. The levers 79 have eyes 90 in which 60 the outer ends of wires 91 are secured. The inner ends of the wires 91 are fastened to a pin 103, carried at the ends of pairs of links 102, one pair of which is pivoted to raised 65 portions of the frame and the other pair

provided with pins engaging in slots in the opposite end of the same raised portion of the frame. The other ends of the wires have pivotally connected thereto links 93 pivotally secured at their opposite ends to 70 the lower end of operating lever 76, which is provided near this point with a curved slot 94 in which a pin 95 travels in order to limit the movements of the operating lever. 75

To impart an intermittent step by step movement to the carriage 15, the wheel 62 is mounted on a coupling sleeve 97 co-operative with another coupling member 98 on shaft 70. A bracket carries a bell-crank 80 lever 99 at its upper end, one arm of which is attached to sleeve 97, while its other arm is engaged by a lever 100 pivoted in the lower part of the same bracket.

The engagement and disengagement of 85 the coupling is effected by a curved arm 101 attached to the lever 100 at one of its ends and the link 102 at its opposite end, the pin 103 around which the wire 91 is wound, is engaged by another wire guided over a 90 roller 104 and carries a weight 105.

In operation, the machine being supplied with an article to be planed, the motor is started and thereafter the entire frame is advanced, intermittently, at the ends of the 95 stroke of the cutter carrying arm, the details of the operating mechanism having been previously given.

Changes may be made in the general arrangement and in the construction of the 100 minor details of the invention without departing from the scope as laid down in the claims.

Having thus described my invention, what I claim as new and desire to secure by 105 Letters Patent, is:—

1. In a planing machine, a carriage for the work-piece, a means for imparting a timed step by step movement to said carriage, an oscillating tool carrier, means for effecting a temporary stopping of said carrier at the stroke-terminals at which time the carriage movement takes place, and means for regulating the length of the sweep 110 of the tool. 115

2. In a planing machine, a carriage for the work-piece, racks on both side edges of said carriage, means in engagement with said racks to move said carriage co-operative, means for imparting to said rack engaging means a step by step motion, an oscillating tool carrying arm, means for moving said arm positively into its end positions at each cut, and means for effecting a temporary stopping of said arm at the 120 stroke terminals at which time the step by step motion takes place. 125

3. In a planing machine, a carriage for the work-piece, an oscillating arm fulcrumed at one end to the machine frame, 130

means at the opposite end of said arm to positively move said arm to the end of a work-piece adjustably held on said carriage, means for allowing an adjustment of the tools carried by said arm to a predetermined length of sweep, and means for rotating said tool.

4. In a planing machine, a carriage for the work-piece, means for imparting to said carriage an intermittent forward motion, an oscillating tool carrying arm, pair of arbor wires connecting the tool carrying arm with said arbors, means for alternately rotating said arbors, and means for slackening said wires for causing the tool carrying arm to dwell for a short time at the end of its stroke.

5. In a planing machine, a carriage for the work-piece, means for imparting to said carriage an intermittent forward motion, a tool carrying means for guiding the tools carried by the carrier across the work-piece to cut a sweep of predetermined length in the work-piece on said carrier, a pair of arbors journaled in the frame, cables connecting said arbors with said tool carrier, clutch members interchangeable with said arbors and an operating lever for operating said clutches to actuate the tool carrier on one and the other side of the machine.

6. In a planing machine, a carriage for the work-piece, an oscillating arm fulcrumed in the machine frame at one end, a tool carrier at the opposite end of said arm, a plurality of tools carried by said carrier, an operating lever, a pair of levers operated by said first named lever, a clutch controlled by said levers, and means for positively engaging said tools with the work-piece.

7. In a planing machine, a frame, an oscillating arm fulcrumed thereto, a power shaft, an oscillating arm, means for cou-

pling said arm to said power shaft, an operating lever adapted to operate said coupling means, tools carried by said oscillating arm, and means allowing an adjustment of the sweep of said tools over the work-piece to a predetermined length.

8. In a planing machine, a weighted operating lever, means for limiting the movement of said lever in any direction, a pair of arbors, an oscillating arm, cables connecting said arm with said shafts or arbors, a pair of links pivotally connected to the lower end of said operating lever, links pivoted intermediate their ends to the machine frame and to said first named links, and wires connecting said last named links to said arbors and wire.

9. In a planing machine, an oscillating tool carrier arm, arbors in the machine frame, cables connecting said tool carrier arm with said arbors, a floating roller over which said wire is guided, a pointer on the shaft of said roller, a dial over which said hand is travelling for indicating the length of a cut, and means for locking the parts in their adjusted positions.

10. In a planing machine, a tool carrier, a carriage for the work-piece beneath said carrier, means for imparting to said carriage a step by step motion, a motor and shaft rotated thereby, a power shaft, a coupling on said shaft for coupling the motor with said carriage, a bell-crank lever attached to one member of said coupling, a second bell-crank lever engaged by said first one, and means for operating said bell-crank levers and coupling members intermittently coupling said carriage to the motor.

In witness whereof I have affixed my signature.

FRANZ SCHULDES.
